United States Patent Office

Des. 226,742
Patented Apr. 17, 1973

226,742

CARRYING CASE

Robert E. Dustin, Brookline, Mass., assignor to Dustin
& Davenport Incorporated, Brookline, Mass.

Filed May 28, 1971, Ser. No. 148,273

Term of patent 14 years

Int. Cl. D3—99

U.S. Cl. D87—1

FIG. 1

FIG. 2

FIG. 3

FIG. 4

FIG. 5

FIG. 1 is a perspective view of a carrying case in an open position, showing my new design;

FIG. 2 is a side elevational view in a closed position;

FIG. 3 is a front elevational view thereof;

FIG. 4 is top plan view thereof; and

FIG. 5 is a bottom plan view thereof.

I claim:

The ornamental design for a carrying case, as shown.
